Application September 17, 1932, Serial No. 633,563

24 Claims. (Cl. 221—95)

Our invention relates in general to dispensing apparatus and more particularly to apparatus for dispensing fluids such as gasoline, although it may have more general application and one of the important objects of the invention is to provide means enabling the operator to control the entire apparatus at the dispensing nozzle. More particularly we contemplate the provision, in a power-operated fluid dispensing apparatus, of means associated with a valved dispensing nozzle for controlling a remote power-operated fluid propelling device in connection with the control of the valved dispensing nozzle. Another object is to provide an electrical control system for a power operated dispensing apparatus having means manually operable at the discharge nozzle of the apparatus for actuating the electrical system to start or stop the power-operated apparatus. Another object is to provide means for actuating the electrical control system at the discharge nozzle without interrupting an electrical current carrying circuit, thus to eliminate sparking and the resulting danger of explosions where inflammable fluids are dispensed.

Another object is to provide an electrically controlled power operated dispensing device for inflammable fluids with means for actuating the electrical control system from the dispensing nozzle without danger of exploding the inflammable fluid being dispensed.

Another object is to provide an automatic, electrically operated, locking device to prevent unauthorized operation of the dispensing device. Another object is to control the dispensing device by mechanically altering the magnetic characteristics of an electric control circuit without interrupting the circuit and thus creating sparks.

Among the other objects and advantages is to provide a simple, inexpensive and safe electrical remote control for a fluid dispensing device; to provide a fluid pressure dispensing device having a valved nozzle with means adjustable to permit the nozzle valve and the fluid pressure control to be actuated in a desired sequence so that the control system may be conditioned to open the valve before or after or at the same time the dispensing pressure is applied to the fluid to force it through the nozzle; to provide a fluid dispensing device, having a flexible discharge hose terminating in a valved nozzle and means to force the fluid under pressure through the hose with an electrical remote control system including electrical means operable from the nozzle to control the operation of the fluid forcing means without breaking the

electrical circuit at the nozzle or in the immediate neighborhood of the hose; and in general to provide numerous other improvements and advantages which will become more clearly apparent from the following description, which, taken with the accompanying drawings, discloses a preferred form of the invention.

Referring to the drawings:

Fig. 1 is a diagrammatic view of a fluid dispensing system embodying our present invention; 10

Fig. 2 is an enlarged view of a part of the apparatus shown in Fig. 1;

Fig. 3 is an enlarged sectional view of a part of the apparatus shown in Figs. 1 and 2;

Fig. 4 is a schematic diagram of the electrical 15 connections forming a part of the system embodying our present invention;

Fig. 5 is a sectional view taken substantially along the line 5—5 of Fig. 3;

Fig. 6 is a sectional view taken substantially 20 along the line 6—6 in Fig. 5;

Fig. 7 is a sectional view taken substantially along line 7—7 in Fig. 3; and

Figs. 8, 9, 10, and 11 are fragmentary views showing modified constructions embodying our 25 invention.

To illustrate our invention, we have shown on the drawings, a fluid dispensing device including a preferably flexible fluid dispensing conduit or hose 11 terminating in a nozzle 13 and means to force the fluid to be dispensed to the hose 11 under pressure. The fluid forcing means may comprise any suitable means but we prefer to employ a pump 15 which is driven by any suitable or convenient motive means 17, the operation of which 35 may be quickly and easily controlled.

In the illustrated embodiment, the device 17 comprises an electric motor and the intake of the pump 15 is connected by means of a suitable conduit 19 with a storage tank 21 for the fluid to be dispensed. The outlet of the pump is connected by means of a conduit 23 to an air release and overflow device 25 and thence by the conduit 27 through suitable metering devices in the housing or standard 29 and through the sight glass 31 45 to the hose 11. The air release device also may have a vent 33 and a return connection 35 to the reservoir 21.

It will be noted that the pump 15 and its driving motor 17, i. e., the devices for forcing the fluid 50 to the nozzle 13 under pressure are shown located in the house 37 at a point remote from the standard 29. The fluid forcing means can, of course, be located in the housing 29 if desired but in any event it is desirable to control the operation of the 55

fluid forcing means from the nozzle so that the operator may start and stop the same while manipulating the nozzle in dispensing fluid. To this end the fluid forcing means is actuated from a suitable electrical power source 39 by means of conductors 41 which lead from the power source through suitable switching and protective devices 43 to the electric motor 17. The conductors 41 also are provided with a control switch 45 normally urged by the spring 47 toward open position but operable by means of the solenoid 49 to close against the influence of the spring 47. The solenoid 49 is included in an electrical circuit 51 including the power source 39, the switching and protective devices 53 and the control device 55. In addition, the circuit may, if desired, include a locking device 57, the operation and function of which will hereinafter be more fully explained. The conductors 41 may and the circuit 51 should, respectively contain switches 58 and 59 preferably mercury switches, which are preferably operatively connected to the tiltable hook 61 carried on the housing 29 and on which the nozzle 13 is adapted to be supported or hung when not in use. The hook is preferably normally moved toward a raised position on the housing 29 by means of the spring 63 and the switches 58 and 59 are arranged to close when the hook is raised by the spring, i. e., when the nozzle is off the hook and ready for action, and to open when the hook is depressed against the urge of the spring by the weight of the nozzle hanging inactively upon it. Alternately the hook 61 may be manually shifted to either raised or lowered position.

When the nozzle is hanging on the hook therefore, the switches 58 and 59 are open and the circuits 41 and 51 are inactive. When the nozzle is removed from the hook, however, the switches 58 and 59 will close and the motor 17 would immediately be set in operation but for the fact that the switch 45, which is open, must be closed before the motor can be started. The motor, therefore, does not start when the switches 58 close as a result of the removal of the nozzle from the hook. When the switch 59 is closed, however, the circuit 51 will be closed and in operating condition. The nozzle 13 embodies a valve 65 which is normally urged by means of the spring 67 to close the nozzle against the discharge of fluid therethrough but has a stem 69 which may be moved to unseat the valve against the urge of its spring. The control mechanism 55 in the circuit 51 is for the purpose of controlling the amount of electrical current flowing in the circuit 51 and is arranged when in normal position, i. e., when the nozzle is closed by the valve 65, to prevent sufficient current from flowing in the circuit 51 to actuate the solenoid 49 to close the switch 45. The control 55, however, is arranged to increase the current in the circuit 51 sufficiently to close the switch 45 whenever the valve stem 69 is depressed to open the valve 65 so that when the nozzle is off the hook and the valve is opened, the motor 17 will be started in operation to force the fluid out through the nozzle; and the parts may be adjusted to cause the motor to start in operation just before or after or at the same time that the valve is opened. To this end the nozzle comprises a fitting having a channel 71 formed for connection at one end with the hose 11, preferably though not essentially, through a fitting 73 containing a valve 75 opening outwardly into the channel 71. The opposed end of the channel 71 is provided for the actual discharge of the fluid. The fitting also provides a valve seat 77 intermediate the ends

of the channel 71 for the valve 65 and a packing gland or bushing 79 may be provided to permit the valve stem to extend out of the fitting in position to be manually depressed by the operator. The nozzle fitting also may be formed as shown in Fig. 3 to provide a mounting for the control 55 which, in the illustrated embodiment, comprises a coil 81 connected in the circuit 51 and wound preferably on the middle arm of an E-shaped core 83, which may be secured in any suitable manner in a casing 85. This casing provides room adjacent the core for a shiftable armature 87 carried on a shaft 89 which extends out of the cover 91 of the casing and terminates in a shackle 93. Within the casing a spring 95 is provided to normally urge the armature 87 to engage and bridge the gap between the ends of the arms of the core. The armature, however, may be retracted against the urge of the spring to increase substantially the air gap in the core of the control device 55. By increasing the air gap the magnetic characteristics of the device are changed so that more current may flow through the coil in response to an electro-motive force of given voltage applied to the circuit 51. In other words, by increasing the air gap in the core of the device 55, more current is permitted to flow in the circuit 51 and the parts are arranged so that when the armature is lifted from the core a predetermined distance, the current in the circuit 51 is increased to a point permitting the switch 45 to close against the spring 47. In order to operate the device 55 in conjunction with the valve 65, a handle 97 is pivoted on the nozzle fitting in position to extend across the protruding end of the valve stem 69 and is shaped to enable the operator to easily grasp it. The free end of the handle is formed as at 99 to co-operate with the cam slot 101 of a lever 103, which is pivoted in the nozzle fitting and which is attached to the shackle 93 of the device 55 by means of the loose pin 105. As the operator manipulates the handle 97 to depress the valve stem 69, the cam follower 99 traveling in the slot 101 will draw the armature 87 away from the core and start the fluid forcing means in operation. The support for the device 55 may be formed as a guard 107 for the handle 97 and the lever 103. The handle 97 also may carry an adjustable screw 109 opposite the end of the valve stem whereby to adjust the operation of the valve in any desired timed relation with respect to the device 55 and the guard 107 may be perforated as at 111 to accommodate the adjusting screw. Means is provided to lock the nozzle on the hook 61 when not in use. The housing 29 is provided with a receptacle 125 to receive the discharge end of the nozzle fitting and the hook has a pin 62 while the guard 107 is provided with a finger 108 adapted to rest on the pin 62. The guard also is provided with an opening 126 to receive a projection 127 on the hook, which projection is formed to receive a locking device 129 to secure the nozzle on the hook and to hold the levers 97 and 103 in the inoperative position shown in Figs. 2 and 3.

The switch 45 is preferably of the toggle type, that is to say, one which makes or breaks contact rapidly so that the switch passes from open to closed position or vice versa practically instantaneously at the appointed instant of operation. The spring 47 also is preferably provided with a means 48 for adjusting the tension thereof in order that the instant of operation of the switch may be regulated to a certain extent by increasing or decreasing the spring tension which operates differentially with respect to the electro-magnetic

switch-operating force set up by the solenoid 49. The switch 45 also may be provided with suitable time delay switch-opening and switch-closing means 50 in order to provide flexibility of operation so that the system may be conditioned to operate in a desired sequence. In certain instances, it may be found desirable to provide the switch with means to delay both opening and closing movements.

10 By means of the adjustment provided by the set screw 109, the system may be conditioned so that the motor starts after the valve is opened and stops before the valve closes or the adjustment may be arranged to cause the motor to start 15 before the valve is open and to stop after the valve closes. It is not essential that the adjustment be provided between the handle 97 and the stem 69 of the valve but it may be applied between the handle 97 and the operating plunger of the 20 electro-magnetic control device 55 in order to control the movement of said operating plunger in conjunction with the movement of the valve plunger 69.

By delaying the opening movement of the switch 45, the stoppage of the motor may be delayed to occur after the valve 65 closes even when the adjustment 109 is set to start the motor after the valve opens so that by means of the switch-opening time-delay device, the motor may be 25 made to start after the valve 65 opens and to stop after the valve 65 closes. By delaying the switch-closing movement, the starting of the motor may be delayed until after the valve is open even where the adjustment 109 has been set to accomplish 30 the stoppage of the motor before the valve closes in order that the system may be conditioned so that the motor starts after the valve opens and stops before the valve is closed.

In other words, the system of our present invention is adjustable to open and close the valve and start and stop the motor in any desired sequence. The motor can be made to start before the valve is opened and to stop before the valve is closed; to start before the valve is opened and to 45 stop after the valve closes; to start after the valve opens and to stop after the valve closes; and to start after the valve opens and to stop before the valve closes. This flexibility in operation has numerous advantages which will be appreciated 50 by any one familiar with this type of apparatus.

As a safety measure and to prevent the device from operating at all unless all parts are functioning properly, we have provided an electrically operated automatic self-locking device 55 comprising a solenoid 113 which is connected in the circuit 51 and hence energized only when the circuit 51 is energized, that is to say, when the switch 58 is closed by removing the nozzle from the hook 61. The solenoid 113 is mounted 55 in a fitting 115 threaded in an opening in line with the valve seat 11 and formed to receive an extension 117 of the valve stem 69. The extension has a groove 119 to receive the locking tip of a member 121 which is carried in the fitting 115 and normally urged toward locking position by the spring 123. The member 121, however, also forms the armature of the solenoid 113 so that when energized, the solenoid will retract the armature and permit the valve 60 stem to be shifted to operate the valve. When the circuit is de-energized, however, the lock member 121 will hold the valve closed and if for any reason the control circuit 51 is not energized when the nozzle is removed from the 65 hook, the valve cannot be opened, nor fluid dis-

pensed. This also prevents unauthorized tampering with the apparatus in order to take fluid from the hose while locked on the hook, as by 70 prying down the stem 69. Our locking device positively prevents the valve 65 from opening 5 while the nozzle is on the hook. It may also be found desirable to provide switch means in the motor power circuit 41 and to control the switch by means of an under voltage relay powered from the circuit 51 so that if, for any reason, the circuit 51 is not energized when the hook 61 is released, the under voltage switch means will open and prevent the motor from 10 operating when the control circuit is inoperative.

The devices 55 and 57 are, of course, located 15 on the nozzle but it will be noted that they simply comprise coils of wire and no electrical circuit is opened at the nozzle. The switches 58 and 59 are sealed mercury switches and are preferably located within housing 29 and hence no sparking 20 is permitted at any spot in the vicinity of the discharge of the fluid. The conductors forming the part of the circuit 51 leading to the coils of the devices 55 and 57 are preferably thoroughly 25 insulated and clad in a flexible metallic sheath 131 which may parallel the hose 11 and be secured thereto by suitable clips 133.

In Figs. 8, 9, and 10, we have shown other embodiments of our invention wherein the control of the power operated fluid forcing means 15 is 30 accomplished by pulling the hose out of its normal free hanging position as when the operator pulls the hose into position to deliver gasoline to an automobile. In these arrangements the motor control, after the system has first been 35 conditioned for operation by removing the nozzle from the hook, is accomplished by a device 155 which, as shown in Figs. 8 and 9, has a function similar to that of the device 55 previously mentioned, or if desired, may be a switch. The 40 device 155 may be mounted on the casing 29, as shown in Fig. 8, or may be mounted on the hose 11, as shown in Figs. 9 and 10. If mounted on the casing, the shiftable element of the device may be connected, by a rigid or preferably 45 by a flexible connector 157, to the hose 11 at a point spaced from its point of attachment on the housing 29. The connector 157 also extends through a guide 159 rigid with the housing 29 and located adjacent the hose 11, so that if the 50 hose is pulled in any direction away from the rigid guide, as it must be to assume any position other than a free hanging position, the connector will be pulled out through the guide and will actuate the device 155 to control the 55 fluid forcing means. The hose may be pulled by the operator in manipulating the nozzle which may, in this instance, be similar to the nozzles shown in Fig. 3, the parts 55, 57, and 103 and functionally associated parts being eliminated. 60

Where the control device 155 is mounted on the hose as in Fig. 9, it is simply necessary to connect the shiftable element of the device to the closest point on the casing 29 by means of a rigid or flexible connector, so that when the 65 hose is shifted from its free hanging position in any direction other than toward the housing itself, the operative parts of the device will be relatively shifted and the desired control effected.

In the embodiment of our invention shown in 70 Fig. 10, the upper part of the flexible hose may include a flexible sylphon or bellows which may be elongated when the hose is pulled and held pulled. This sylphon may have an encircling or concentric control device having parts 181 75

and 181 corresponding to the parts 81 and 87 of Fig. 5 and arranged in collar or sleeve-like form, the part 181 being mounted stationarily on the upper portion of the sylphon and the lower or relatively movable portion of the sylphon carrying the shiftable core 187 like 87 of Fig. 5 mounted concentrically thereon and flexibly shiftable toward and away from the parts 181, so that when the hose is pulled the sylphon 10 will be stretched and the core part 187 will be shifted with respect to the stationary coil parts 181 whereby to alter or change the flow of current through the circuit 51 as heretofore described in connection with the device of Fig. 4. 15 Such a form of device will be operable on pulling the hose in any direction. The natural tendency of the flexible or resilient sylphon to return to normal position would restore the control device in like manner to the action of the spring 95 20 of Fig. 5. In place of a sylphon, any approved type of resilient coupling having relatively shiftable parts may be used, it being understood that when the hose is pulled, one part of the coupling will be moved relatively to the other, and these 25 parts would be provided with the electrical control device of Fig. 5.

In accordance with another embodiment of our invention, we propose as shown in Figure 11 to provide the housing 29 with an upper over-hanging portion 141 enclosing a rotatably mounted drum 143, adapted normally to be rotated in one direction by suitable spring means. This drum is provided with an axially located conduit or pipe 145 which may be connected to the discharge of a sight glass, or to the discharge of the meter through which gasoline is forced from the pump. This axial pipe terminates in a flexible hose 11 which normally coils on the drum. The end of the flexible hose is provided with a 35 valve controlled nozzle 13, and the nozzle is adapted to project through an opening 147 in the housing, the arrangement being that when desiring to dispense gasoline, the operator grasps the projecting nozzle and pulls so as to rotate the drum 40 and draw out the hose to desired length. The drum is provided with a lug 149 adapted to move a control lever 151 when the drum is rotated to shift suitable control means, such as a mercury switch 153, to start the pump motor. Suitable 45 adjustments are provided for regulating the time at which the pump motor starts when the drum is rotated. On return movement, the operator lets the spring rotate the drum to coil the hose upon the drum within the housing. Preferably 50 a hand controlled lever is provided for pre-setting the motor starting mechanism which thereafter becomes automatically operable on rotating the drum by a pull on the hose. This is necessary in order to comply with fire 55 writers' demands. In this rotating drum type of device, the housing is provided with a shutter or closure which locks the nozzle in the housing except for only a portion of the discharge end.

The main portion of the nozzle is wholly 60 closed, and hence the valve lever or control cannot be operated inadvertently. The shiftable shutter on the housing may be padlocked in closed position. Thus, in this device, rotation of the drum in one direction through a desired angular 65 degree, automatically starts the pump, and after the finish of the dispensing operation, the rotation of the drum by the spring, automatically actuates the mechanism to stop the pump. The lug for shifting the pump motor starting lever 70 may be angularly adjustable on the drum to con-

trol the time of starting and stopping the motor of the pump. Suitable means is provided for controlling the tension of the spring urging the drum to rotate so as to control the speed of the winding and unwinding of the hose. By having 5 the drum elevated so that the nozzle depends at a sufficient elevation, better access is had to the hose and more facility in the unwinding, and particularly the winding operation is provided, and no particular support need be provided for 10 the depending hose. The starting and stopping of the pump motor is controlled by pulling out the hose, this causing rotation of the drum, and the automatic operation of the pump motor.

The constructions shown in Figs. 8, 9, and 10 are 15 simple and inexpensive and have the advantage that the control device is removed from the immediate neighborhood of the nozzle. If desired, the automatic locking device may be incorporated in the embodiments shown in Figs. 8, 9, and 20 10 and also may be omitted in the embodiment first described herein, since the same, while a useful improvement, is by no means an essential feature.

It is thought that the invention, and its numerous attendant advantages, will be fully understood from the foregoing description and it is obvious that numerous changes may be made in the form, construction and arrangement of the several parts without departing from the spirit 30 or scope of the invention or sacrificing any of its advantages.

Having thus disclosed our invention, what we claim as new and desire to secure by U. S. Letters Patent is:

1. Fluid dispensing apparatus comprising, in combination, a conduit through which fluid may be forced, fluid-forcing means associated with the conduit, and electrically actuated means for controlling the fluid-forcing means comprising 40 means forming an electrical circuit operatively associated with said fluid-forcing means, and means in said circuit operable from the discharge end of the conduit without interrupting the circuit for controlling the fluid-forcing means by 45 altering the electrical characteristics of said circuit.

2. Fluid dispensing apparatus comprising a conduit through which fluids may be discharged, fluid-forcing means associated with the conduit 50 to force fluid therethrough, valve means at the discharge end of the conduit for controlling the flow of fluid through the conduit and electrically actuated means for controlling the fluid-forcing means comprising means forming an electrical circuit operatively associated with said fluid-forcing means, and means in said circuit operable from the discharge end of the conduit in 55 timed relationship with respect to the operation of the valve means whereby to alter the electrical characteristics of said circuit without interrupting the same whereby to stop and start the fluid-forcing means.

3. Fluid dispensing apparatus comprising fluid-forcing means, a conduit through which fluids 65 may be forced by the forcing means, valve means at the discharge end of the conduit, an electrical circuit including operable means for controlling the flow of current in said circuit without interrupting the same, and means, responsive to the 70 current flow in said circuit, for controlling the fluid-forcing means, and means for actuating the operable means and the valve means in timed relationship.

4. Fluid dispensing apparatus comprising fluid- 75

forcing means, flexible means forming a conduit associated with the fluid-forcing means and through which the fluid may be discharged, and means, for controlling the operation of the fluid-forcing means from the discharge end of the conduit, comprising an electrical circuit operatively associated with the fluid-forcing means, and shiftable means operable from the discharge end of the conduit and associated with the circuit for changing its electrical characteristics, without opening the circuit at the discharge end of the hose whereby to effect control of the fluid forcing means.

5. Fluid dispensing apparatus comprising fluid-forcing means, flexible means forming a conduit associated with the fluid-forcing means and through which the fluid may be discharged, said conduit having manually operable valve means at its discharge end for controlling the flow of

20 fluid therefrom, and means, to control the operation of the fluid-forcing means from the discharge end of the conduit, comprising an electrical circuit operatively associated to control the fluid-forcing means in response to variations 25 of current flowing in said circuit, and shiftable means operable from the discharge end of the conduit and associated with the circuit for varying the current flow in said circuit, without opening the circuit at the discharge end of the hose.

30 6. Fluid dispensing apparatus comprising fluid-forcing means, flexible conduit-forming means associated with the fluid-forcing means and through which the fluid may be discharged, and electrically-operated means, for controlling the 35 operation of the fluid-forcing means from the discharge end of the conduit, comprising an electrical circuit operatively associated to control the fluid-forcing means in response to variations of current flowing in said circuit, inductive means 40 included in said circuit, and shiftable means operable from the discharge end of the conduit for varying the reactive effect of said inductive means in order to vary the current flowing in the circuit.

45 7. Fluid dispensing apparatus comprising fluid-forcing means, flexible conduit-forming means associated with the fluid-forcing means and through which fluid may be discharged, and means to control said fluid-forcing means from 50 the discharge end of said conduit, said means including an electrical circuit, and means mounted on the conduit and operable from the end thereof to affect the electrical characteristics of the circuit, without opening the circuit at the discharge 55 end of the hose whereby to effect control of the fluid forcing means.

8. A remotely controlled fluid discharge system including fluid-forcing means, a discharge conduit associated with the fluid-forcing means 60 to discharge the fluid at a remote point, a manually operable valve in the conduit at the remote discharge end, electrically actuated means for controlling the fluid-forcing means, and a control for said electrically actuated means, said control 65 including an electrical circuit extending to the discharge end of the conduit and operatively associated with said electrically actuated means for controlling the same in response to the change 70 in the electrical characteristics of said circuit, means manually operable in conjunction with the valve and operatively associated with said circuit for varying the electrical characteristics thereof without opening the circuit at the discharge end of the conduit in order to control the

fluid-forcing means in a desired sequence with respect to the operation of the valve.

9. A remotely controlled fluid discharge system including fluid-forcing means, a discharge conduit connected thereto, manually operable valve 5 means controlling the flow of fluid through the discharge conduit, control means for controlling the operation of said fluid-forcing means, means forming an electrical circuit operatively associated with said control means for actuating the 10 same in response to changes in the electrical characteristics of said circuit, and means operatively associated with the conduit and associated with the circuit and operable from the discharge end of the conduit to change the electrical 15 characteristics of the circuit without interrupting the same whereby to effect control of the fluid forcing means.

10. A remotely controlled fluid discharge system including fluid-forcing means, a discharge 20 conduit connected thereto, manually operable valve means controlling the flow of fluid through the discharge conduit, control means for controlling the operation of said fluid-forcing means, means forming an electrical circuit operatively 25 associated with said control means for actuating the same in response to changes in the electrical characteristics of said circuit, and means mounted on the conduit and operatively associated with the circuit and operable at the discharge end of 30 the conduit to change the electrical characteristics of the circuit without interrupting the same, and means to render the circuit inoperative when the conduit is not in use.

11. A remotely controlled fluid discharge sys- 35 tem including fluid-forcing means, a discharge conduit connected thereto, manually operable valve means controlling the flow of fluid through the discharge conduit, control means for controlling the operation of said fluid-forcing means, 40 means forming an electrical circuit operatively associated with said control means for actuating the same in response to changes in the electrical characteristics of said circuit, and means mounted on the conduit and operatively associated with 45 the circuit and operable at the discharge end of the conduit to change the electrical characteristics of the circuit without interrupting the same, a hook on which to hang the conduit when not in use, and means associated with the circuit and 50 controlled by the hook for rendering the circuit inoperative when the conduit is hanging on the hook.

12. A remotely controlled fluid discharge system including fluid-forcing means, a discharge 55 conduit connected thereto, manually operable valve means controlling the flow of fluid through the discharge conduit, control means for controlling the operation of said fluid-forcing means, means forming an electrical circuit operatively as- 60 sociated with said control means for actuating the same in response to changes in the electrical characteristics of said circuit, and means mounted on the conduit and included in the circuit and operable at the discharge end of the conduit to 65 change the electrical characteristics of the circuit without interrupting the same, and locking means associated with said valve means for securing it in closed position when the system is not in use, said locking means being actuated by 70 the circuit to unlatch the valve means to condition the device for use.

13. In a fluid delivery apparatus comprising a housing, a hose hanging on the housing and swingable to various delivery positions with re- 75

spect to the housing, fluid forcing means connected to the hose, means including an electrical circuit for controlling the fluid forcing means, a device including a stationary portion connected 5 in said circuit and a relatively shiftable element for changing the electrical characteristics of said stationary portion without interrupting the circuit whereby to control the fluid forcing means and means operable from the discharge end of 10 the hose to shift the shiftable element.

14. In a fluid delivery apparatus comprising a housing, a hose hanging on the housing and swingable to various delivery positions with respect to the housing, fluid forcing means connected 15 to the hose, means including an electrical circuit for controlling the fluid forcing means, a device including a stationary portion connected in said circuit and a relatively shiftable element for changing the electrical characteristics of said 20 stationary portion without interrupting the circuit whereby to control the fluid forcing means, means to mount the stationary portion on the hose, and means operable from the discharge end of the hose to shift the shiftable element.

15. In a fluid delivery apparatus comprising a housing element, a hose element hanging on the housing element and swingable to various delivery positions with respect to the housing element, fluid forcing means connected to the hose element, means including an electrical circuit for 30 controlling the fluid forcing means, a device including a stationary portion connected in said circuit and a relatively shiftable member for changing its electrical characteristics without interrupting the circuit, means to mount the stationary portion on one of said elements and a flexible mechanical connection for connecting the shiftable member to the other of said elements so that the parts may be relatively shifted by 35 40 pulling on the hose element and shifting it with respect to the housing element.

16. A gasoline dispensing device including means forming a delivery conduit provided in its length with an extensible portion and a pair of 45 relatively shiftable electrical control elements on said extensible portion and adapted to be relatively shifted in response to extension of the extensible portion responsive to a pull on said conduit means.

17. A fluid delivery apparatus comprising a conduit, through which fluid may be forced, and having a delivery end adapted to be adjusted to various delivery positions and to inactive position, fluid-forcing means associated with said 50 conduit, means including an electrical circuit for controlling the operation of the fluid-forcing means in accordance with electrical conditions in said circuit, means operatively associated with the said circuit and adapted for actuation from the fluid delivery end of said conduit for changing the operating conditions in said circuit without 55 interrupting the same for the purpose of controlling the fluid-forcing means, and means, with which said conduit is co-operatively associated 60 65 when in its inactive position, for rendering said electrical circuit inactive.

18. A gasoline dispensing device including means forming a delivery conduit provided in its length with an extensible portion and a pair of 70 relatively shiftable electrical control elements on said extensible portion and adapted to be relatively shifted in response to extension of the extensible portion responsive to a pull on said conduit means, means to deliver gasoline through 75 said conduit, and means to control the delivery

means electrically including an electrical circuit having a portion operatively associated with said relatively shiftable control elements at the extensible portion of said conduit means.

19. A gasoline dispensing device, including 5 means forming a flexible delivery conduit, a pair of relatively shiftable electric control elements at least one of which is mechanically connected with said delivery conduit and movable with respect to the other element in response to a pull on said conduit means, means to deliver gasoline through said conduit, and means to control the delivery means electrically including an electrical circuit having a portion operatively associated with said relatively shiftable control elements whereby the 10 delivery means may be controlled by manipulation at the discharge end of said flexible conduit.

20. Fluid dispensing apparatus comprising, in combination, a conduit through which fluid may be forced, fluid forcing means associated with 20 the conduit, and electrically actuated means for controlling the fluid forcing means comprising means forming an electrical circuit operatively associated with said fluid forcing means, means in said circuit operable from the discharge end 25 of the conduit for controlling the fluid forcing means, and adjustable time delay means in said circuit for delaying the operation of the electrically actuated means.

21. Fluid dispensing apparatus comprising, in 30 combination, a conduit through which fluid may be forced, fluid forcing means associated with the conduit, a valve for controlling delivery of liquid through the conduit, electrically actuated 35 means for controlling the fluid forcing means in timed relationship with respect to the operation of said valve comprising means forming an electrical circuit operatively associated with said fluid forcing means, control means in said circuit, means operable at the discharge end of said conduit for opening and closing said valve and for actuating the control means in definite timed 40 relationship, and time delay means operatively associated with said circuit to effect control of the fluid forcing means in timed relationship 45 with respect to the opening and closing of said valve.

22. Fluid dispensing apparatus comprising, in combination, a conduit through which fluid may be forced, fluid forcing means associated with 50 the conduit, a valve for controlling delivery of liquid through the conduit, electrically actuated means for controlling the fluid forcing means in time relationship with respect to the operation of said valve comprising means forming an electrical circuit operatively associated with said fluid forcing means, control means in said circuit, means operable at the discharge end of said conduit for opening and closing said valve and for actuating the control means in definite timed 55 relationship, and time delay means operatively associated with said circuit for maintaining the fluid forcing means in operation until after the closure of the valve.

23. Fluid dispensing apparatus comprising, in 65 combination, a conduit through which fluid may be forced, fluid forcing means associated with the conduit, a valve for controlling delivery of liquid through the conduit, electrically actuated 70 means for controlling the fluid forcing means in timed relationship with respect to the operation of said valve comprising means forming an electrical circuit operatively associated with said fluid forcing means, control means in said circuit, means operable at the discharge end of said con- 75

duit for opening and closing said valve and for actuating the control means in definite timed relationship, and time delay means operatively associated with said circuit and operable to start the fluid forcing means in operation before the valve opens.

24. Fluid dispensing apparatus comprising, in combination, a conduit through which fluid may be forced, fluid forcing means associated with the conduit, a valve for controlling delivery of liquid through the conduit, electrically actuated means for controlling the fluid forcing means in timed relationship with respect to the operation

of said valve comprising means forming an electrical circuit operatively associated with said fluid forcing means, control means in said circuit, means operable at the discharge end of said conduit for opening and closing said valve and for actuating the control means in definite timed relationship, time delay means operatively associated with said circuit and operable to start the fluid forcing means in operation before the valve opens and to maintain the fluid forcing means in operation until after the valve closes. 5 10
